SHELF FOR REFRIGERATOR OR FREEZER OR SIMILAR ARTICLE

John K. Wagner, Marengo, and Louis R. Marz, Homestead, Iowa, assignors to Amana Refrigeration, Inc., Middle Amana, Iowa, a corporation of Delaware

Filed Nov. 24, 1965, Ser. No. 88,211

Term of patent 14 years

(Cl. D67—3)

Fig. 1

Fig. 3

Fig. 2

Fig. 4

Fig. 5

FIG. 1 is a top plan view of our design for a shelf for refrigerator or freezer or similar article showing our new design;

FIG. 2 is a front elevational view;

FIG. 3 is a bottom plan view;

FIG. 4 is a rear elevational view; and

FIG. 5 is a perspective view taken from the top thereof.

The dominant features of our design reside in the portions shown in full lines in the drawings.

We claim:

The ornamental design for a shelf for refrigerator or freezer or similar article, substantially as shown and described.
